UNITED STATES PATENT OFFICE.

DANIEL J. MURNANE, OF SAN MATEO, AND DANIEL J. MURNANE, JR., OF SAN FRANCISCO, CALIFORNIA, ASSIGNORS TO NON-PRESSURE GLAZING COMPANY, OF SAN FRANCISCO, CALIFORNIA, A CORPORATION OF CALIFORNIA.

SASH FOR HOLDING GLASS.

Application filed September 16, 1925. Serial No. 56,657.

Our invention relates to metallic sashes for holding the glass of windows and show cases, and particularly to division and corner bars for holding large and heavy sheets of plate 5 glass.

One of the objects of the invention is the provision of improved and simplified sash members, readily and cheaply formed from sheet metal, and which largely obviate the 10 danger of breakage of the glass, due to the simplicity of the assembling and the freedom of stresses upon the glass. Another object of the invention is the provision of an improved tie bar for use in holding the sash 15 members together.

The invention possesses other objects and features of advantage, some of which, with the foregoing will be set forth in the following description of the preferred form of our 20 invention which is illustrated in the drawings accompanying and forming part of the specification. It is to be understood that we do not limit ourselves to the showing made by the said drawings and description, as we 25 may adopt variations of the preferred form within the scope of our invention as set forth in the claims.

Referring to the drawings:

Figure 1 is a horizontal sectional view 30 taken thru a vertical division bar.

Figure 2 is a side elevation of the tie bar element of our invention, the direction of the view being indicated by the arrow 2 of Figure 1.

Figure 3 is a plan view of the tie bar, the direction of view being indicated by the arrow 3 of Figure 2.

Figure 4 is a horizontal sectional view thru a corner bar embodying our invention.

In terms of broad inclusion our sash 40 comprises a stationary sash bar conveniently of U-shaped section and having secured on the inside thereof a bracket. Our invention includes the manner in which this bracket is 45 secured to the bar. The stationary sash bar engages one side of the glass, and on the other side of the glass is the adjustable sash bar. Fastening the two together is a tie bar interlocked in the adjustable sash bar and extending 50 across the bracket to which it is clamped by a screw. In order to prevent the tie bar from moving when the clamping screw is seated upon it, the underlying portions of the

bar are corrugated so that the head of the screw imbeds itself in the corrugations. The 55 tie bar itself is formed from a single piece of sheet metal, portions at one end being turned to provide a foot engageable in the adjustable sash bar. It may be desirable to interpose a shoe plate between the stationary 60 sash bar and the glass and in this case we provide an integral tongue on the bracket engageable with the shoe to secure it in place.

In detail, our invention comprises a vertical sash bar member 2, preferably of U-shaped section as shown in Figure 1. The edges of this member are turned back to provide glass-engaging beads 3. At intervals in the length of the sash bar apertures are provided for the mounting of the brackets 4. 65 These brackets are formed with an aperture 6 surrounded by an annular flange 7, and are permanently secured to the sash member by expanding the annular flange in the sash apertures, as shown in Figure 1.

The bracket is formed to provide a seat 8 lying about midway between the side walls of the sash bar and at the free end is bent to form a leg 9 engaging the side wall of the sash bar. A rib 10 gives the required stiffness 80 to the bracket structure.

On the opposite side of the glass 11 is the adjustable sash bar 12 having inwardly turned glass-engaging flanges 13 on each side. Means are provided for fastening the adjustable sash bar to the stationary sash bar, and such means comprises a tie bar placed opposite each bracket thruout the length of the sash bars. The tie bar is formed at one end 85 with a slot 14, bordered by corrugations 15, 90 and this end of the tie bar is adapted to overlie that portion of the seat of the bracket 8 directly underneath the aperture 6. A screw 16 having a head 17 is threaded into the bracket concentric with the aperture 6, and 95 is accessible therethru, so that separate holes in the U-bar for this purpose are unnecessary.

Preferably the underside of the screw head is cone-shaped, and the adjacent portion of the bracket surrounding the screw is complementary in form, so that when the screw is tightened down upon the tie bar, the corrugations are forced into the conical depression in the seat by the coned screw head, which also imbeds itself in the corrugations. The 100 105 corrugated end of the tie bar provides a

conformable portion in which the head of the clamping screw seats without tending to move the tie bar. Thus no undesirable stresses are exerted on the glass.

- 5 The other end of the tie bar is formed to provide a foot 19 adapted to be engaged behind the glass engaging flanges 13 of the adjustable sash bar. Preferably the tie bar is formed from a single sheet of thin metal a 10 tongue being struck up from the remainder of the sheet to form that portion carrying the slot and corrugations. Liberal use is made of ribs 21, and flanges 22, to stiffen the tie bar structure.
- 15 Figure 1 shows a division bar for use between two plates of glass lying in substantially the same plane. My invention may also be embodied in a corner bar, as shown in Figure 4, for holding two sheets of glass lying at 20 an angle to each other. In the latter case the ends 23 of the tie bar foot 19 are bent, as shown in Figure 4 to accommodate it to the angular sash member 24, the shape of which, is of course, dictated by the angle between the 25 plates of glass.

In either the division bar structure shown in Figure 1, or the corner bar structure shown in Figure 4, we may interpose a shoe plate between the stationary sash bar and the 30 glass; and in Figure 4 I have shown such a shoe plate 26, having rolled edges 27 in which the edges of the U-shaped member 2 seat. To secure the foot plate in place we provide on each of the brackets 8, a tongue 28 which 35 may conveniently be struck out of the leg 9. The shoe plate is provided with apertures thru which the ends of the tongues may project, and a slight twisting of these ends with a pair of pliers, after assembling the shoe 40 plate upon the U-shaped member, is sufficient to hold it in place.

We claim:

1. A sash for holding glass comprising a stationary member adapted to engage one 45 side of the glass, an adjustable member adapted to engage the other side of the glass, a tie bar secured to one of said members and having a corrugated end, a bracket on the other member, and clamping means embedding in said corrugated end for locking the bar to the bracket.
2. A device for locking two members together, comprising a bar secured to one of the members and having corrugations therein, a 55 seat for the corrugated portion of the bar arranged on the other member, and clamping

means arranged on said seat and having a head embedding in said corrugations.

3. A device for locking two members together, comprising a bar secured to one of the members and having corrugations therein, a seat for the corrugated portion of the bar arranged on the other member, and a headed screw threaded into said seat and embedding in said corrugations. 60

4. A device for locking two members together, comprising a bar secured to one of the members and having a recess therein bordered by corrugations, a seat for the corrugated portion of the bar arranged on the other member, a screw threaded into said seat and extending thru the recess in said bar, and a head on said screw embedding in said corrugations. 70

5. A sash for holding glass comprising a 75 stationary member adapted to engage one side of the glass and having an aperture therein, an adjustable member adapted to engage the other side of the glass, a tie bar secured to said adjustable member, a bracket having an aperture bordered by an annular flange, said flange being seated in the aperture in said stationary member to secure the bracket thereto, and a screw for locking the tie bar to the bracket concentric with the 80 bracket aperture. 85

6. A sash for holding glass comprising a stationary sash bar, an adjustable sash bar, a tie bar secured to one of said sash bars, a bracket secured to the other sash bar, means 90 for locking the tie bar to the bracket, a shoe plate interposed between the bracket sash bar and the glass, and means on the bracket for securing the shoe plate to the bracket sash bar. 95

7. A sash for holding glass comprising a stationary sash bar, an adjustable sash bar, a tie bar secured to one of said sash bars, a bracket secured to the other sash bar, means for locking the tie bar to the bracket, a shoe plate interposed between the bracket sash bar and the glass, and an integral tongue on the bracket engaged in said shoe plate. 100

8. In a window sash, a tie bar comprising a single piece of sheet metal cut and formed to provide a tongue having a corrugated end and spaced between opposite edges of the piece and extending at right angles thereto. 105

In testimony whereof, we have hereunto set our hands,

DANIEL J. MURNANE.
